(57) **CLAIM**

The ornamental design for an mobile device holder with an accessory mechanism, as shown and described.

DESCRIPTION

FIG. 1 is a perspective view of a mobile device holder with an accessory mechanism showing our new design attached to a mobile device and coupled to a mobile device grip; FIG. 2 is a perspective view of the mobile device holder with an accessory mechanism of FIG. 1, shown coupled to a mobile device grip;

FIG. 3 is a rear view thereof;

FIG. 4 is a front view thereof;

FIG. 5 is a left-side view thereof;

FIG. 6 is a right-side view thereof;

FIG. 7 is a bottom view thereof;

FIG. 8 is a top view thereof;

FIG. 9 is a perspective view of the mobile device holder with an accessory mechanism of FIG. 1, shown attached to a mobile device;

FIG. 10 is a perspective view of the mobile device holder with an accessory mechanism of FIG. 1, shown without environmental subject matter;

FIG. 11 is a rear view thereof;

FIG. 12 is a front view thereof;

FIG. 13 is a left-side view thereof;

FIG. 14 is a right-side view thereof;

FIG. 15 is a bottom view thereof; and,

FIG. 16 is a top view thereof.

The broken lines in FIG. 1 showing a mobile device and a mobile device grip, and the broken lines in FIGS. 2–8 showing a mobile device grip, and the broken lines in FIG. 9 showing a mobile device, illustrate environmental subject matter only and form no part of the claimed design. All other

(Continued)

broken lines illustrate portions of the mobile device holder with an accessory attachment mechanism that form no part of the claimed design.
